UNITED STATES PATENT OFFICE.

PAUL BURKHARDT, OF ALBION, MICHIGAN, ASSIGNOR TO UNION STEEL PRODUCTS COMPANY, OF ALBION, MICHIGAN.

RACK FOR BAKED GOODS.

Application filed November 9, 1925. Serial No. 67,945.

This invention relates to improvements in racks for baked goods.

The main object of this invention is to provide an improved rack for baked goods such as pies, which is of large capacity; although compact in structure, and from which the pies or other articles may be easily removed.

Objects pertaining to details and economies of my improvements will definitely appear from the detailed description to follow.

I accomplish the objects of my invention by the devices and means described in the following specification. The invention is clearly defined and pointed out in the claim.

A structure which is a preferred embodiment of my invention is clearly illustrated in the accompanying drawing forming a part of this application, in which:

Fig. 1 is a front perspective view of a rack embodying the features of my invention designed as a pie rack.

Fig. 2 is an end elevation, parts being broken away to facilitate the showing of structural details, articles being indicated on certain shelves by dotted lines.

Similar reference numerals indicate similar parts in both views.

Referring to the drawing my improved rack comprises a front frame 1 and rear frame 2 of wires to which wire netting is secured forming a bottom wall 3, end walls 4 and a top wall 5. The vertical wire slats 6 form the rear wall.

I provide a plurality of shelves consisting of the border frames 7 of wire to which the netting 8 is secured. These shelves are arranged within the walls and secured as by means of the wire ties 9 connecting the shelf frames to the end walls.

The vertical partition rods 10 are disposed through the shelves and form a partition dividing each shelf into compartments. In front of each compartment is a guard 11, the same being formed of a piece of wire bent to a bail-shape, the arms of the guard 12 being secured to the front members of the shelves and to the bottom member of the front frame. The guards are arranged so that their ends are spaced from the end walls of the rack and also from the partition members 10, thereby providing openings at the ends of the guards facilitating the grasping of pies or other articles indicated by dotted lines 13 in Fig. 2.

This permits the shelves being arranged closely together and at the same time the articles upon the shelves may be conveniently grasped for removal.

Having thus described my invention what I claim as new and desire to secure by Letters Patent is:

A rack of the class described comprising top, bottom, end and rear walls, a plurality of shelves comprising border frames and wire grids secured thereto arranged within said walls, partition rod like members disposed vertically through meshes of said shelves and secured at their ends to the top and bottom walls, and bail-shaped guard members disposed in upright position with the ends of their arms secured to the front members of the shelf frames in spaced relation to the partition members and the end walls of the rack providing spaces facilitating the grasping of the articles upon the shelves.

In witness whereof I have hereunto set my hand.

PAUL BURKHARDT.
